DRYING TUMBLER HAVING OPERATION
SEQUENCE CONTROLSHubert C. Ellis, Evanston, Ill., assignor to The
Ellis Drier Company, Chicago, Ill.

Application October 3, 1945, Serial No. 619,948

12 Claims. (Cl. 34—45)

1

This invention relates in general to a clothes drier and cooler of the reversing tumbler type which is set for periodic operation to automatically complete a cycle of movements and operations for receiving, drying, cooling, and opening the drier for discharging and recharging.

In removing the moisture content from clothes, fabrics, and other materials in a dry tumbler of this type, it is desirable not only to insure that the apparatus is operated a sufficient time to thoroughly dry the material in the tumbler, but also to expedite the operation, it is necessary that the clothes or other materials be delivered at such a temperature that they may be freely handled in a relatively cool condition.

It is therefore an important object of the present invention to provide a drier of the clothes tumbler type having means for automatically controlling the application of heat for a predetermined period and then reducing the heat or applying a cooling so that the contents of the drier may be delivered in dried condition and at such a temperature that it may be freely handled without danger to the operator.

Another object of the invention is to provide new and improved means for circulating the heating and cooling medium within a drier, to regulate the heat and the time of applying it, to reduce the heat by tempering it, and to turn off the heat and apply a cooling medium. A further object of the invention is to provide means for collecting and removing lint from the heating and cooling circulating line, storing it within the drier casing for removing it from time to time.

A further object of the invention is to provide controlling means in connection with the drier for automatically operating the cylinder and fan motors in timed relation to the cycle of drying operations and opening and closing the charging door of the drier.

Still a further object of the invention is to provide improved means for raising or lowering the tumbler cylinder to bring it opposite the charging opening of the drier when the drier is stopped for unloading and recharging.

Still a further object of the invention is to provide a combined electrical pneumatic and mechanical system of operation for opening and closing the charging door and moving the damper by pneumatic means, for controlling the operation of the electric motors for driving the tumbler cylinder in reverse directions, and for operating the air circulating fans, and also for operating various mechanical constructions such as a lint collector and discharger.

2

Still a further object of the invention is to provide an improved system for controlling a drier having a predetermined cycle of operations, having safety switches, over load and low voltage relays, automatic door switches and signal lamps to indicate when one or both of the motors are running.

Another object of the invention is to provide a dry tumbler which is generally of new and improved construction and is characterized by simplicity of design and operation as well as ease and facility of assembly and use.

Other objects of the invention and various advantages and characteristics of the present dry tumbling apparatus and system of operation will be apparent from a consideration of the following detailed description.

The invention consists in the several novel features of construction and operation which are hereinafter described and more particularly defined by the claims at the conclusion hereof.

In the drawings which accompany and form a part of this specification or disclosure and in which like letters and numerals of reference denote corresponding parts throughout the several views:

Figure 1 is a front elevation of a dry tumbler in accordance with this invention, with a portion of the upper cover and casing broken away;

Figure 2 is an end elevation of the drier shown in Figure 1 at the driving end;

Figure 3 is an end elevation of the other end of the drier;

Figure 4 is a rear view with parts broken away to show the circulating fans, heat coils, and air ducts;

Figure 5 is a transverse sectional view of the drier; Figure 5A is a fragmentary detail showing a recirculating type of drier;

Figure 6 is an enlarged sectional view illustrating the damper operation;

Figure 7 is an enlarged view illustrating the damper adjustment and control;

Figure 8 is a detail plan view as taken on the line 8—8 of Figure 7;

Figures 9 and 10 are transverse and longitudinal sectional views respectively illustrating the lint collector and its drive;

Figure 11 is a view of the front of the controller;

Figure 12 is a vertical sectional view of the controller showing one of the operating switches in elevation;

Figure 13 is another vertical sectional view through the controller showing some of the op-

erating and indicating parts therein in elevation;

Figure 14 is an elevational view with the controller casing cover removed showing the operating levers and the normally open and normally closed valve members operated thereby;

Figure 15 is a sectional detail view of the charging door safety switch; and

Figure 16 is a wiring diagram of the motor circuits and the controlling connections therefor in the control box also showing diagrammatically the air control lines for the door and damper cylinders.

The present invention may be applied either to a drier of the once through type as shown and described more particularly in this application with air drawn in, heated, circulated through the tumbler, and expelled, as indicated in Figure 5, or to the recirculating type in which air drawn into the casing is heated, and recirculated through the tumbler as many times as desired, as indicated by the structure shown in Figure 5A which is substituted for the once-through arrangement shown in Figure 5.

This invention covers a cycle of operations. The clothes or other material to be dried are deposited in the dryer cylinder in wet or damp condition, the cylinder is sufficiently charged, the door thereto is closed, the outside door of the casing is closed, the driving motor for the tumbler cylinder may then be operated; heated air is then applied for a predetermined time after which it is automatically shut off and relatively cold air is admitted so that the contents of the cylinder is cooled sufficiently to permit handling. The cylinder is stopped, the casing cover is raised and if the opening of the cylinder is not in register with the opening in the casing, the cylinder may be moved step by step in either direction to register the door openings. The cylinder door is then opened and the contents withdrawn and the cylinder may then be recharged for another operation.

Referring now more particularly to the drawings, a perforated tumbler cylinder 25 is rotatably mounted at its ends in horizontal position in a casing having a cylindrical enclosing wall 26 with an air inlet opening 21 at the top and an air outlet opening 28 at the bottom of the cylinder extending lengthwise thereof.

At the front of the casing is a hinged door comprising sections 29, hinged at the top to the upper portion of the casing and having a hinged lower portion 30 with a flange 31 at its lower edge abutting a flange 32 projecting outwardly from the casing at the bottom of the door opening.

In the tumbler cylinder 25 are a number of perforated flights 33 for causing a thorough intermingling and tumbling movement of the materials in the cylinder. Between adjacent flights are door sections 34 transversely slidable in groove supports 35 at the edges thereof with the sections in different paths so that the sections 34 may be moved in overlapping relation to provide an opening adapted to register with the door opening in the casing, whereby the contents of the cylinder may be easily removed and a new charge inserted.

Extending from the back of the casing and over the inlet opening 21 is a hot air passageway 36 and a cold air passage 37 formed by an exterior casing wall 38 which may have a two part hinged door 39 normally closable over the passageway but capable of being opened for access to the passageway.

Separating the hot and cold passageways are

perforated valve partitions 40 and 41 extending upwardly from the edges of the inlet opening 21 across the passageways and dividing them from each other, the partitions being inclined together at the top and affording an angular space 42 above the inlet opening. Extending lengthwise in the space 42 is a valve or damper shaft 43 suitably supported by bearing members 44 secured to the cover wall 38. Mounted on the partitions and extending inwardly are a number of supporting arms 45 each having a bolt 46 extending oppositely therefrom with valve plates 47 and 48 spaced from each arm by short sleeve sections 49 mounted on the bolts between the arm and plates with coil springs 50 surrounding the sleeve sections and tending to press the plates outwardly against the head 51 at one end and a fastening nut 52 at the other end. With this construction the valve or damper plates 47 are resiliently seated against their partitions at either end of their movement.

The shaft 43 extends beyond the casing at one end where an arm 53 is secured thereto having spaced extremities 54 between which is mounted a screw pivot 55 through which a regulating screw 56 extends and is locked in any adjusted position by a set screw 57. At the other end of the regulating screw is a hand wheel 58 by means of which the screw is adjusted. Adjacent the hand wheel is a screw block 59 connected to one end of a regulating lever 60 by means of a threaded stud 61 extending through the end of the lever and into the screw block 59. This lever is freely mounted on the shaft 43 and has an opposite extremity 62 pivotally connected to an end-piece 63 at the end of a piston rod 64. This piston rod has a piston 65 at its other end movable in a damper or valve operating cylinder 66. The end of the cylinder has a supporting member 67 mounted upon a pivot 68 secured to the casing 38 so that the cylinder is capable of a slight swinging or oscillating movement due to the connection of the piston rod with the lever arm 62. By adjusting the regulating screw, the throw and movement of the damper or valve plates 47 and 48 may be adjusted so that the plate 47 will seal the opening in its partition 40 and the valve plate 48 will seal the opening in its partition 41 at the limits of movement of the piston 65 and the double valve or damper structure may be positioned at an intermediate location to permit a mixture of the hot and cold air through the partitions 40 and 41.

An atmospheric air inlet comprising a screen 69 and a holding frame 70 is provided at the top of the cold air passageway 37 adjacent the damper valve.

In the hot air passageway 36 are a number of steam pipes 71 connected through the ends of the casing and having end fittings 72 and valves 73 for connecting them to suitable steam supply pipes 74 and for controlling the heat within the heating passageway 36. At the back of the casing and at the end of the heating passageway, most remote from the inlet valve, is an air inlet comprising screens 75 and frames 76 for holding the screens in place. Atmospheric air is then admitted through the screens 75 and passes through the heating passageway 36 where the air is heated by the steam pipe 71 before it is introduced into the tumbler cylinder.

In the lower portion of the casing and at one side of the air outlet 28 are exhaust fans 77, each having a casing with a central inlet opening 78 for receiving air from within the casing and discharging from a spout 79 through an opening

in the casing, closed by a screen 80 and held in place by a clamping frame 81.

Interposed between the air outlets 28 and the discharge fans 77 is a lint removing device comprising an inner screen 82 semi-circular in form and of relatively fine mesh backed and supported by an outer and stronger screen 83 of relatively coarse mesh. A partition 84 completes the closure of the space between the lint remover and the bottom of the casing so that all of the air and other material which passes through the tumbler cylinder and is withdrawn by the suction of the fan 77 must pass through the lint screenings. The lint collects so rapidly that means must be provided for removing the accumulation or the efficiency of the air-flow will be greatly diminished. For this purpose a brush-like wiper 85 is mounted on arms 86 secured to a longitudinally extending shaft 87 so that the rotation of the shaft will cause the wiper to engage its screen 82 collecting and discharging the lint from the bottom of the screen as the wiper is moved.

In order to effect this movement this shaft 87 projects through one end of the casing where a ratchet wheel 88 is secured to the shaft. A ratchet lever 89 is freely mounted on the shaft and has one arm which carries a spring pressed pawl 90 for engaging the ratchet wheel in one direction of movement. From the other arm of the lever a connecting rod 91 is pivoted on a shoulder screw 92 secured eccentrically to the end of a shaft 93 which supports the tumbler cylinder at this end. A fan motor 94 is preferably mounted at the outside of the casing and secured directly to a common shaft 95 for all of the fans within the casing. A cylinder motor 96 is also preferably supported at the outside of the casing and at the same end as the fan motor 94 and it is connected to the tumbler cylinder by reversing and reduction gearing 97 which is not shown in detail but is operative to drive the cylinder at a relatively slow speed such as thirty-six revolutions per minute, reversing its movement after about five or six movements in each direction. With this construction the eccentric connection of the lint remover will operate with a step by step motion regardless of the direction of rotation of the tumbler cylinder.

At each end of the casing is a door operating cylinder 98 having a pivot 99 at its lower end permitting the upper end to oscillate slightly and extending from the upper end of the cylinder is a piston rod 100 having a projecting door bracket 101 at its upper end adapted to engage in a recess 102 at the end of the door section 29 so that as the pistons are thrust upwardly the door is raised and as the pistons are pulled downwardly the door is closed.

Secured to the inside of the casing adjacent the lower edge of the door opening is a switch assembly 103 having a projecting movable part 104 adapted to be engaged by the lower door section 30 when the door is pulled downwardly by the door cylinders 99. When the door is open the switch is open, and when the door is closed the switch is closed thereby closing a circuit so that the cylinder motor may be started. This insures that the casing door is closed before the tumbler cylinder can be operated.

A control box 105 is mounted at the motor end of the casing and comprises a front cover 106 in which a drying timer 107 and a cooling timer 108 are mounted adjacent the top having inde-

pendent setting mechanisms 109 and 110 respectively. In the cover are a number of openings through which controlling parts extend for operation or observation. These parts are as follows: The fan motor has a starting switch button 111, a stop switch button 112 and a fan indicating lamp 113; an inching switch has a starting button 114, an inch-up stopping button 115 and an inch-down stopping button 116; the cylinder motor has an indicating lamp 117, a safety on and off switch button 118, and damper and door levers 119 and 120 extend through operating slots 121 and 122 respectively; visible and accessible through the front cover plate. Within the panel box 105 each of the operating levers 119 and 120 controls the operation of two valves one a normally open valve 123 and the other a normally closed valve 124, secured to a common mounting block 125 which is connected to a source of fluid pressure supply by a pipe 126. Each lever, as 119, is mounted by a pivot 127 in a support 128 below the block 125 and has a projection 129 connected by a pivot 130 with the lower end of a link 131. One end of the pivot 130 projects laterally into the path of a movable armature 132 of a magnet 133 so that the lever can be moved freely upward in its slot 121 but when the magnet 133 is energized its armature will engage the arm 129 or the projecting portion of the pivot 130 which will push the lever 119 and its link connection 131 downwardly to the bottom of its slot. Extending laterally from the link near its upper end are bearing pins 134 which extend into slide bars 135 mounted in glide blocks 136 spaced apart to allow the link 131 to move therebetween, the glide bars having stems 137 extending upwardly into the normally open and normally closed valve blocks 123 and 124. The normally open and normally closed valves for the damper cylinder are connected by pipes 138 and 139 with opposite ends of the damper cylinder 66 and the normally open and normally closed valves of the door operating lever 120 are connected by pipe connections 140 and 141 with the opposite ends of the door cylinders 98.

Each of these normally open and normally closed valves has a connection through pipe 126 (Figure 12) to the source of fluid pressure supply, a pipe connection to one end of the cylinder to which it relates, an exhaust pipe 142, and valve means (not shown, within the valve) actuated by the movement of the operating levers. When pressure is admitted through the normally closed valve to one end of a door cylinder, the other end of the cylinder is connected to exhaust through the normally open valve, and this connection is reversed through the valves for actuating the door cylinder reversely.

Lint removed from screen 82 by wiper 85 collects in a pile 23 at the bottom of the casing. Lint removal doors 24 are hinged at their tops at the front of the casing and tend to swing to closed position. A door may be opened without stopping the cylinder 25 or fans 77 and the lint raked or otherwise removed therefrom, the doors swinging closed by their weight and additionally closed by the suction within the casing.

In a recirculating type of drier, the essential drying, lint removing, and controlling parts are the same, but as shown more particularly by Figure 5A, there is an air inlet opening 75a in the rear wall of the drier casing communicating with the interior of the casing, provided with a screen

76a and a closable door 80a. Extending from the fan 77 is a discharge spout 79a which communicates with the bottom of the heating passageway 36 and forces air therethrough which is drawn into the face through its inlet opening 18, from the bottom of the casing.

Instead of providing a discharge opening through the casing for the fan discharge spout, a closure 81a is applied to the opening over which the screen 80 extends as shown in Figure 5, thus making it possible to utilize the same casing for both types of driers. In the recirculating type, air is drawn in through the door 80a which may swing freely inward or may be fastened in closed position, the air being continuously recirculated through the heating chamber, the tumbler, and through the lint removing device. The air thus reused is continuously heated and requires less heat from the heating coils than where fresh air is drawn continuously from the outside of the casing circulated through the drier and then expelled therefrom by the fan.

In both forms of driers, the operation of the tumbler, the lint removing device and the controlling mechanism is the same.

In operation, the drying timer 107 is first set for the desired drying time and the cooling timer 108 includes the time covered by the drying timer 107 plus the time for the cooling timer. These timers are spring operated and have normally open and normally closed switches for automatically controlling the operation of the hot and cold air double valve or damper in accordance with the times for which the timers are set.

To start the tumbler cylinder motor and assuming that the cylinder doors are closed but that the casing doors are open, the door closing lever 120 is raised which admits fluid under pressure to the door cylinder 98 for closing the door. This closes the door interlock switch 103 shown in Figure 15 which allows electrical connections to be made through the driving and other motors. Control switch 118 is turned to the "on" position and by pressing cylinder start button 114, a control circuit is closed for operating the main line switches to admit current to operate the cylinder motor. This also releases the motor brakes and starts the timer motor which energizes the forward and reverse contactors to alternate the reverse driving mechanism approximately six times per minute.

To start the fan motor, press the fan start button 111 which is maintained normally in closed position for continuously actuating the fan motors. In the normal cycle of operations, the movement of the tumbler cylinder is continued for the drying time, then the valve or damper is changed reducing the heat applied to the drying cylinder and applying cold air thereto for a predetermined time, after which the tumbler cylinder is stopped and the casing door is automatically opened. To stop the tumbler cylinder at any time for emergency or other reasons, it is necessary only to operate the cylinder and fan stop buttons 118 and 112 respectively. If it is necessary to raise or lower the tumbler cylinder to make it register with the casing door opening, the cylinder start button 114 is pressed and to inch the cylinder up or down, the buttons 115 and 116 are operated as required. This will position the door of the tumbler cylinder to register with the open door of the casing so that dried and cooled material may be easily removed from the tumbler cylinder, and the tumbler cylinder recharged with the same or other material as desired.

In carrying out the cycle of operations, the cylinder motor 96 is represented in the diagram, Figure 16, as a three-phase motor having current supply mains 150, 151 and 152 with a fused knife switch 153 for connecting them respectively to main conductors 154, 155 and 156, in which are circuit breaker switches 157 controlled by an electrical switch maintaining device 158 having a normally open interlock 159 for controlling the opening and closing of these circuit breaker switches.

The cylinder motor 96 is connected for reverse rotation by switches 162 and 163 controlled by a reverse electrical switch device 164, and by conductors 160 and 161 and connected between main conductor 154 and 156 having switches 162 and 163 and switches 165 and 166 controlled by a forward electrical switch device 167, the arrangement being such that when the forward device 167 is energized, switches 165 and 166 are closed and current is supplied to the cylinder motor 96 to cause its rotation in one direction, and when the other reverse switch device 164 is energized, current is supplied to the cylinder motor to cause its rotation in the reverse direction of rotation. This reversal is controlled by a reversing timer 168 which alternately energizes the forward and reverse switch devices approximately six times per minute in the present invention.

30 The switch 153 is assumed to be closed and to start the cylinder motor, the door lever 120 is raised which closes the door by means of the door cylinders 98. This closes the door safety switch 104 and the control switch 118 is turned to "on" position, the cylinder start switch 114 being depressed momentarily and closing a circuit through switch device 158 and its normally open interlock and releasing the brakes indicated by a magnet winding 168 for the cylinder motor 96 whenever the cylinder motor is energized. This circuit is traced from main 156 adjacent switch 153 by means of conductor 169 having a fuse 170 therein to contact P1 of switch 118, lower conductor 171 of this switch, conductor 172 maintaining interlock 159, conductor 159a to the P5 contact of lamp 117, thence through conductor 179, door switch 104, conductor 177, front contacts of inch-up switch 115, conductor 176, front contacts of inch-down switch 116, conductor 175, contact 213, conductor 174 to P8 contact of cylinder start switch 114, thence through conductor 194, switch maintaining device 158, conductor 188, switch 190, conductor 191, switch 192, conductor 193, contact P3 of the control switch 118, upper contact 180 of switch 118 to contact P2 and thence through conductor 181, fuse 182 back to supply main 155. This control circuit actuates the switch maintaining device 158 closing the switches 157, the normally open interlock switch 159 being also closed when the switches 157 are closed and opening the switches through the maintaining device 158 when it is open.

Closing the switches 157 sets up an energizing circuit for releasing the brake 168 by means of 65 a conductor 183 connected to one of the mains 156, thence through the brake magnet 168 to another supply main 155.

Closing the switches energizes the timer 168, alternately moving the switch contact member 70 184 to engage contacts 185 or 186. Switch contact 184 is connected to the conductor 194 which is connected as traced above to main 156, and either of the contacts 185 or 186 is connected through conductors 196 or 199 respectively to 75 conductor 199 respectively and thence by con-

ductor 198 to conductor 189 which leads, as traced above, to the other supply main 155.

When the cylinder start switch 114 is depressed, a circuit is thereby closed from terminal contact P6 by way of conductor 187 through the back contacts of the switch, conductors 188, 173, electrical switch maintaining device 158, conductor 189, overload relay switch 190, conductor 191, overload relay switch 192, conductor 193 and switch contact P3 thereby completing the circuit. A circuit is also closed from contact P6 through conductor 172, interlock device 159 for the switch maintaining device 158 by way of conductor 159A to one terminal P5 of cylinder motor indicating lamp 117 and thence by conductor 179 to safety contact P3 completing the circuit.

A circuit is also closed through the door switch from starting switch contact P6 through conductor 187, back contacts of cylinder start switch 114, conductor 188, conductor 174, conductor 175, front switch contacts of inch-down switch 116, conductor 176, front contacts of inch-up switch 115, conductor 177, door switch 104, conductor 178 to one terminal of cylinder motor indicating lamp 117 and thence through the lamp and by conductor 179 to the other safety switch terminal P3.

With the above circuits and connections established, the cylinder motor is in operation, the cylinder indicating lamp 117 is lighted and the release of pressure on the cylinder start switch allows its contact bar to reestablish connections between front contacts P7 and P8.

When the cylinder start switch is released, a maintaining circuit is traced from contact P6 of the safety switch through conductor 172 maintaining switch 159, conductor 159A, conductor 178, door switch 104, conductor 177, inch-up switch 115, conductor 176, inch-down switch 116, conductor 175, conductor 174 to the cylinder start switch and thence through conductor 173 and switch maintaining device 158, conductor 189, switch 190, conductor 191, switch 192, conductor 193 to the other safety switch terminal P3.

An energizing circuit is also established through the reversing timer 168 which may be traced from the safety switch 118 to the contact P8 of the cylinder starting switch by the path above set forth and thence through contact switch 114, P7 contact thereof, conductor 194, reversing timer 168, conductor 195, and thence through switch 190, conductor 191, switch 192, and conductor 193 to the opposite safety switch terminal P3.

Actuated by the reversing timer is the switch contact member 184 which is alternately moved to engage contact 185 in one direction, or contact 186 in the other direction. This contact member is connected through conductor 194 and when moved to engage contact 185, it closes a circuit from conductor 194 through contacts 184 and 185, conductor 196, forward electrical switch device 167, and conductors 197 and 198 to the conductor 189, thus energizing the electrical switch device 167 and closing reversing switches 165 and 166. When the switch contact member 184 makes engagement with contact 186, a circuit is closed from conductor 194 through contacts 184 and 186, conductor 199, through reverse electrical switch device 164 and thence through conductor 198 to conductor 189 and to the safety switch contact P3 by the circuit previously traced, thereby energizing the reverse electrical switches 162 and 163.

In the main line on the forward electrical reversing switch side is an overload and low voltage

electrical tripping device 200 for controlling switch 190 and for the reversing switches 162 and 163. The switch 192 is controlled by an overload and low voltage electrical tripping device 201, both of which are automatically operated to protect the cylinder motor 96 and to open the controlling circuits if the voltage falls too low or the load is too great.

The drying timer 107 (Figure 16) is set for a predetermined length of operations and has a switch 202 operated thereby at the end of the set time for controlling a solenoid 203 with an armature 204 (representing magnet 133 and its armature 132 of Figure 12) movable for tripping the damper lever 119 and opening the damper switch 119S. Tripping the damper lever actuates the damper cylinder 66 and moves the damper from a drying to a cooling position.

In a similar manner, the cooling timer 108 has

a switch 205 operated thereby at the end of a set period, and included in a circuit with a solenoid

206 which operates an armature 207 to trip the door lever 120, opening a switch 120S and opening normally closed valve 124 (Figure 12) for admitting fluid under pressure to the door cylinders

98 for opening the casing door when the cooling

operation is complete. Switches 119S and 120S

are shown diagrammatically in Figure 16 in line with their respective solenoid armatures 204 and

207 controlled by the drying timer solenoid 203

and the cooling timer solenoid 206. Switch 119S operates to cut the drying timer out of the circuit so that the cooling timer can then take over the operation. The circuits for these two timers

35 comprises a conductor 208 connected to the safety switch contact P6 at one side of each of the switches 119S and 120S. From the other side of switch 119S, a conductor 209 extends to the solenoid winding 203, thence through switch 202 of

40 the timer 107 and by means of conductors 210 and

211 to the opposite terminal P3 of the safety switch 118. For the cooling timer, a conductor

212 leads from the other side of the switch 120S through the solenoid winding 206 and timer

45 switch 205 to conductor 211 and thence to the other contact P3 of the safety switch 118.

With this connection of the timers, the drying timer will maintain the tumbler cylinder in operation under drying conditions for the period

50 for which timer 107 is set, and at the expiration of the time, switch 202 will be opened, breaking the circuit through solenoid 203 and dropping the damper lever 119; the cooling timer will continue the operation of the cylinder motor for a

55 further predetermined period, whereupon the operation of the solenoid will trip the door lever, actuating the door cylinders 98 raising the door

60 and opening the door safety switch 104 which opens the controlling circuit through the switch

65 maintaining device 158 which opens the main circuit breaker switches 157, thereby opening the circuit to the cylinder motor 96 and deenergizing the brake solenoid 168 to stop the tumbler cylinder.

If it happens that the cylinder door does not

register with the casing door opening when the cylinder is stopped, it may be necessary to raise

or inch up the door side of the cylinder a small amount, less than one rotation, or to lower or

70 inch down the door side of the cylinder a small amount for the same reason. This is accomplished by simultaneously pressing the cylinder

start button 114 and either the inch up button

115 or the inch down button 116.

75 Since the door switch 104 is open at this time

11

it is necessary to establish a temporary control circuit which does not include the door switch. Assuming that the inch up switch is operated to engage its rear contacts, this circuit may be traced as follows:

From contact P6 of safety switch 118 by way of conductor 187 back contacts of cylinder start switch 114, conductors 188, 174, to back contact 213 of inch-up switch 115, thence through conductor 214 to forward electrical device 161, conductors 197, 198, switch 190, conductor 191, switch 192 and conductor 193 to the other terminal P3 of safety switch 118. This energizes the forward main switches 165 and 166 closing an operating circuit through them to the cylinder motor 96 which will be maintained only as long as the inch-up switch is depressed. At the same time the previously traced circuit will be closed through the cylinder start switch by way of conductor 173 through the switch maintaining device 158 and 189 back through the switches 190 and 192 to the terminal P3 of the safety switch 118.

Depression of the cylinder start switch breaks the switch connection between front terminals P8 and P1 thereby opening the circuit through conductor 194 which leads to the reversing timer 188.

Similarly when the inch down switch is depressed engaging its back contacts at the same time the cylinder start switch is depressed an energizing circuit is traced through the inch down switch as follows:

From safety switch terminal P6, conductor 187, cylinder start switch, back contacts, conductors 188, 174, 175, conductor 214 to the back contact 215 thence through switch 116 to terminal P4 conductor 216 to conductor 199 and through electrical switch device 164 and energizing reversing switches 162 and 163 thence through conductor 198, switch 190, conductor 191, switch 192, conductor 193, to the opposite terminal P3 of the safety switch 118. In either case the inch up or the inch down switch is simply pressed in for a brief interval to rotate the cylinder in the corresponding direction, and a circuit is closed through the cylinder motor indicating lamp 117 to light the lamp, as previously traced.

The fan motor 94 is operated separately from the cylinder motor and is independent of the door and damper cylinder operations. The fan start button 111, the fan stop button 112 and the fan indicating lamp 113 are mounted upon the control box 105 for convenience and although in the diagram figure 22, the current supply means 150A, 151A and 152A are represented as different than the supply means for the cylinder motor, in practice they are the same. A fused knife switch 217 connects the supply means to main conductors 218, 219 and 220 leading through circuit breaker switches 221 to the fan motor 94 represented as a three-phase alternating current motor. In at least two of the phases are overload and low voltage relays 222 for controlling switches 223 and 223' connected in series and to a switch maintaining device 224 for the circuit breaker switches 221. This maintaining device 224 is in turn controlled by an electric interlock 225 and circuits from these controlling devices lead to the fan start and fan stop switches for which the controlling circuits are as follows:

When the fan start switch is depressed to engage the back contacts P11 and P12 thereof, the following circuit is closed from the safety switch contact P6, through conductors 187 and 230 to back contact P12 through fan start switch 111

12

to the contact P11; thence through conductor 233, front contact P14, fan switch 112, contact P10, conductor 230, switch device 224, conductor 228, switches 223, conductor 227, switch 223', conductor 226 to the other switch terminal P8. At the same time a circuit is closed through the fan start switch contact P11, conductor 230, electric interlock device 225, conductor 231, and thence to the safety switch contact P3. A lighting circuit is also closed through the fan indicating lamp 113 from the fan start back contact P11, conductor 234, fan indicating lamp 113, conductor 235, and thence through conductors 218 and 211 to the safety switch contact P3.

To stop the fan, the fan stop switch 112 is depressed, thus breaking the connection between the conductors 233 and 230, thereby breaking the connection for the switch maintaining device 224 and causing the switches 221 to open, thereby opening the main circuit to the fan motor.

With this construction, it will be seen that the complete operation of the machine is entirely controlled from the control box 105, that after the time of drying and cooling is set, the operation of the machine is continuous for the cycle of operations thereof and the cycle may be initiated by raising both of the levers 119 and 120. The motor operation can be stopped at any time by turning the safety switch 118, and if there is any electrical fault such as an overload or insufficient current which would tend to damage the electrical apparatus, the reversing switches will be opened stopping the cylinder motor or the fan motor. The indicating lamps 113 and 117 will be lighted when the cylinder operating motor 96 and the fan motor 94 are in operation, and when the cycle of operations is complete, the cylinder will be stopped and the outer cylinder door will be automatically opened. When the controlling apparatus voltage is the same as that of the mains, conductors 189 and 181 are connected to safety switch contacts P1 and P2. To change the voltage applied to the controlling apparatus from that which is applied to the mains, conductors 188 and 181 are disconnected and a transformer 240 is connected by conductors 239 and 238 to mains 219 and 220 as shown in dotted outline (Figure 16), and is connected by conductor 238 to safety switch contact P2 and by conductors 237 and 231 to safety switch contact P1.

The drying time and the cooling time for any clothes or other materials to be washed is determined somewhat by the nature of such materials and before the tumbler is set in operation, the setting mechanisms 109 and 110 at the top of the control panel which resemble the hands of clocks are positioned for the desired time of drying and the desired time of cooling. The clothes or other material to be dried are deposited in the tumbler in wet or damp condition when the outer hinge door 29 is opened and registers with door 34 in the tumbler. The tumbler door is closed by sliding it endwise and after the casing door 29 is closed, the drier may be set in operation. The door 29 is closed by raising the door closing lever 120 which closes the door interlock switch 103, allowing electrical connections to be made through the driving and other motors. The control switch 118 is turned and by then pressing start button 114, the motor for operating the tumbler is energized and the tumbler is alternated approximately six times per minute.

The fan for removing the lint is actuated by pressing the fan start button 111 and may be

stopped by pressing the fan stop button 112. To observe whether the fan motor is running, the lamp 113 at the front of the panel is lighted when the fan is in operation. Likewise the lamp 117 indicates at the front of the panel when the tumbler motor is in operation.

During the drying operation, the valve at the top of the tumbler is opened to admit heat from the hot air passageway 36 after the time determined by the setting of the drying timer and after the predetermined time has elapsed, a circuit is closed by the timer which causes the operation of the valve opening and connection from the cold air passage 37 and closing the hot air passage. The operation of the tumbler then continues for the time set on the cooling timer, after the expiration of which, the tumbler motor circuit is opened by the operation of the cooling switch 205.

During the operation of the drying tumbler, the lint removing device continues in operation and if it is desired to remove the lint or any portion thereof, the door 24 in the casing is opened and the lint or dirt removed therefrom without affecting the operation of the tumbler.

When the tumbler cylinder is stopped, after the contents has been sufficiently cooled, the door of the tumbler cylinder may not register with the door of the casing. In this case, it is necessary either to press the inch-up button 115 or the inch-down button 116 which causes the movement of the tumbler in a corresponding direction to register the door openings. The contents is taken out and the tumbler cylinder may then be recharged for another complete cycle of operations.

The various detailed operations of each of the separate parts are described in connection with the structural description. Likewise the circuit connections are all described and traced in detail. It is also pointed out that the tumbler cylinder motor may be stopped at any time by turning the safety switch 118 and when the cycle of operations is complete, both of the levers 119 and 120 are at the bottoms of their slots. It is necessary to raise them both to repeat the cycle of operations.

Various changes may be made in the construction, combination, and arrangement of the various parts, and the invention is not to be understood as restricted to the specific construction, combination, and arrangements as herein set forth as these may be modified within the scope of the appended claims without departing from the spirit and scope of the invention.

Having thus described the invention, what I claim as new and desire to secure by Letters Patent is:

1. In a drier of the class described, a casing having a cylindrical chamber with an air inlet and an air outlet, a perforated tumbler cylinder rotatable in the chamber, an exhaust fan in the casing for receiving the air from the outlet and discharging it from the casing, an electric driving motor for the exhaust fan, an electric operating motor for rotating the tumbler cylinder, valve means comprising a valve having opposed seats and a valve head movable between the seats for admitting relatively hot and cold air to the casing inlet for the tumbler, fluid pressure means for actuating the valve means to open, close, and partially open the valves, a hinged door for the casing for access to the tumbler cylinder, fluid pressure means for opening and closing the door, timing means for operating the

5 valve means and controlling the fluid pressure means to close the casing door, to operate the cylinder driving motor to drive the tumbler cylinder, and to stop the cylinder driving motor when the cylinder door mechanism is operated to open the door.

2. In a drier of the class described, a rotatable tumbler cylinder, a casing for the cylinder having an air inlet and an air outlet, means comprising a valve having opposed seats and a valve head movable between the seats for admitting relatively hot and cold air at the inlet, a fan in the casing for removing air in the outlet, a door in the casing having means for opening and closing the door, an electrical door switch closed by the door in its closing position and opened when the door is raised, a driving motor for the cylinder having a circuit including the door switch, and clock means for producing a timed cycle of operations comprising means whereby the cylinder operating motor is started after the door switch is closed by closing the door, means for opening one valve and admitting hot air to the cylinder for a predetermined period, said means 10 partially closing the hot air valve and opening the other to admit relatively cold air to the cylinder for a period to cool the contents of the tumbler cylinder, means for stopping the tumbler cylinder and means for opening the casing and thereby operating the door switch to prevent further operation of the tumbler cylinder motor.

3. In a drier of the class described, a tumbler cylinder, a casing in which the cylinder is rotatable having an air inlet and an air outlet at opposite sides of the cylinder, means for admitting hot air to the inlet, means for admitting cold air to the inlet, a valve structure comprising a valve having opposed seats and a valve head movable between the seats for closing off the hot air or for closing off the cold air, a fluid pressure valve operating cylinder connected to operate the valves, a lever for controlling fluid pressure to the cylinder having open and closed positions, a normally open valve structure and a normally closed valve structure for controlling fluid pressure to said cylinder and operated by the movement of said lever, and a pair of clock timers, one comprising connected means for maintaining the operating lever in a position to admit heat through the valve structure for a predetermined time, and the other timer comprising connected means for operating the lever to close the hot air valve for the admission of hot air to the tumbler cylinder and to open the cold air valve for the admission 30 of cold air to the tumbler cylinder for a predetermined time.

4. In a drier of the class described, a tumbler cylinder, a casing in which the tumbler cylinder is rotatable having an air inlet and an air outlet in the casing, means for admitting hot and cold air through the air inlet, said means including a valve structure comprising a valve having opposed seats and a valve head movable between the seats, an operating cylinder for moving the valve structure in reverse directions, a lever and a valve operated thereby for controlling fluid pressure to the operating cylinder and the valve structure comprising a normally open valve and a normally closed valve reversely operated thereby, and clock timing means including an operative connection therewith for maintaining the controlling lever in one position for a predetermined time to actuate the operating cylinder piston for opening the hot air valve structure to the admission of heat to the cylinder, and for moving the operating

lever to cooling position for opening the cold air valve to admit cooling air to the cylinder for a predetermined time.

5. In a drier of the class described having a rotatable tumbler cylinder, an electric motor for driving the cylinder, means for admitting hot and cold air to the cylinder, a timer including an electrical switch for controlling the time of the admission of hot air, another timer including an electrical switch for controlling the time of admitting the cold air, magnets controlled by the said timer switches, an operating lever for the hot and cold air means, a door for the drier and a fluid motor for opening and closing it, an operating lever for controlling the fluid motor for closing and opening the door, and electro-responsive means in connection with the timers and magnets and operated by the switches thereof for actuating the levers to operate said hot and cold air means and also to open the door in predetermined relation.

6. In a drier of the class described, a tumbler cylinder, an electric motor for rotating it in a casing, the casing having a door and fluid pressure means for opening and closing the door, a lever for controlling the fluid pressure means, means for admitting hot and cold air to the tumbler cylinder and including a valve operated by a fluid pressure device, a lever for controlling fluid pressure to said valve device, one of said levers being raised to control the admission of hot air through the valve and lowered to admit cold air therethrough, the other lever being raised to control the closing of the casing door and lowered to control the opening of the casing door, and timers including switches and electro-responsive means for actuating the levers to move them from raised to lowered position thereby first operating the valve and then opening the door.

7. In a rotary drier, a casing having a tumbler cylinder rotatable therein, the casing having a door and fluid pressure means for raising and closing the door, a door in the tumbler cylinder, an electric motor for driving the tumbler cylinder, electrical supply and circuit controlling means for actuating the motor to drive the cylinder and including a door switch in the motor circuit operated by the casing doors in closing and opening, valve means for admitting hot and relatively cold air to the cylinder, electrical clock operated timing means for predetermining the time of admission of the hot air, electrical clock operated timing means for predetermining the time for admission of the relatively cold air, the cylinder having a door which is stopped to register with the casing door, means for automatically stopping the motor when the cold air admission time is complete, and means to control the fluid pressure means to open the casing door when the motor stops, thereby opening the door switch in the motor circuit.

8. In a drier of the class described having a tumbler cylinder rotatable in the casing, the cylinder having manually operated doors, the casing having a door and fluid pressure means for opening and closing the door, fluid pressure operated valve means for admitting hot and relatively cool air to the cylinder, levers manually operable, one for controlling the door cylinder fluid pressure means, and the other for controlling the fluid pressure valve means, and electrical timing means including switches for closing electrical circuits and electro-magnetic devices in circuit with said switches, one circuit for operating the lever which controls the door opening and

closing fluid pressure means and the other circuit for operating the lever which controls the valve cylinder operating means.

9. In a drier of the class described, the combination of a rotatable tumbler cylinder, a casing in which the cylinder is rotatable, valve means for admitting hot and relatively cold air to the cylinder, a door in the casing having fluid pressure door operating means, fluid pressure valve operating means including hot and cold air valve, a fan for drawing hot and cold air through the cylinder, a motor for operating the fan and control means for the drier comprising a control panel, levers extending through the panel and movable relatively therein for controlling the door operating fluid pressure means and the valve fluid pressure operating means, a pair of adjustable timers for predetermining the timing of the hot air and cold air valve operating means, said timers each comprising a switch operated thereby, a circuit and an electro-responsive device controlled by the switch and actuated to operate one of the levers, switches movable in the panel to control circuits for starting and stopping the cylinder motor for starting and stopping the fan motor, lamps in the panel for indicating when the cylinder motor is in operation and when the fan motor is in operation, one circuit device being operative to move one of the levers from raised to lowered position to control the operation of the valve operating means changing the valve means to cut off hot air and to admit cold air to the tumbler cylinder, and the other circuit device being operative to move the other lever to down position for controlling the operation of the fluid pressure device door operating means to open the door.

10. In a drier of the class described, the combination of a cylinder and a casing in which it is rotatable, of a motor and means for driving the cylinder in reverse directions in the casing, a door in the casing and fluid pressure means for opening and closing it, means for admitting hot and relatively cool air to the cylinder comprising a valve and a fluid pressure cylinder for operating the valve, a motor fan for drying air through the cylinder and a common control box for timing, controlling and operating the drier parts comprising a panel having levers projecting therethrough and movable manually upward, timing means in the panel having electrical means operated thereby for tripping the levers to move them downwardly, one of the levers operating the fluid pressure door means, and the other of the levers operating the fluid pressure valve means.

11. In a drier of the class described having a rotatable tumbler cylinder, a casing in which the cylinder is mounted, valve means for admitting hot and relatively cool air to the cylinder, a door in the casing, fluid pressure means for operating the casing door, a fluid pressure cylinder for operating the valve means, timing means for controlling the admission of hot and cold air to the cylinder by means of the valve means, an electric driving motor for the cylinder, a pair of manually raisable operating levers, an electric circuit, switches and electro-responsive devices in connection with the levers for controlling the operation of the motor and the operation of the fluid pressure cylinder when the levers are relatively moved, the levers actuating the fluid pressure controlling means, and the levers being moved in a reverse direction by their electro-responsive devices for reversely actuating said fluid

pressure means and the switches in connection with an controlled by said levers.

12. In a drier of the class described, a rotatable tumbler cylinder, a casing in which the cylinder is mounted, valve means for admitting hot and relatively cool air to the cylinder, fan means for drawing air through the cylinder, a driving motor for the cylinder, a door in the casing, fluid pressure means for operating the door, and a fluid pressure means for operating the valve means, a pair of manually raisable operating levers and electrical switches therefor, timing means, circuits and electric-responsive devices operable separately and in conjunction with each of said levers for first closing the casing door, starting the cylinder motor and admitting hot air to the cylinder when the levers are manually moved in one direction for continuing the admission of hot air for a predetermined time and thereupon operative to open a switch in a circuit effective to operate one of the levers in a reverse direction and to actuate the valve cylinder for admitting cool air for a remaining predetermined time, the operation of one lever being effective to stop the cylinder motor and thereafter the timing means being effective to open another circuit and to automatically move the other lever to open the casing door thereby completing the normal cycle of operations.
